(57) **CLAIM**

The ornamental design for a trench roller as shown and described.

DESCRIPTION

FIG. 1 is a left-rear perspective view of a trench roller of the present invention;

FIG. 2 is a right-front perspective view thereof;

FIG. 3 is a left-front perspective view thereof;

FIG. 4 is a right-rear perspective view thereof;

FIG. 5 is a rear view thereof;

FIG. 6 is a front view thereof;

FIG. 7 is a left view thereof;

FIG. 8 is a right view thereof; and,

FIG. 9 is a top view thereof.

Portions of the trench roller shown in broken lines in FIGS. 1-9 form no part of the claimed design.

1 Claim, 9 Drawing Sheets
